(57) CLAIM

The ornamental design for a clothing box, as shown and described.

DESCRIPTION

The file of this patent contains at least one drawing/photograph executed in color. Copies of this patent with color drawing(s); photograph(s) will be provided by the Office upon request and payment of the necessary fee.

FIG. 1 is a top, front, left perspective view of a clothing box showing my new design in a closed position;

FIG. 2 is a top, front, left perspective view thereof in a partially open position;

FIG. 3 is a front view thereof in a closed position;

FIG. 4 is a rear view thereof in a closed position;

FIG. 5 is a left side view thereof in a closed position;

FIG. 6 is a top, front perspective view thereof in a closed position;

FIG. 7 is a bottom, front perspective view thereof in a closed position;

FIG. 8 is a right side view thereof in a closed position;

FIG. 9 is a top, front, left perspective view of another embodiment thereof in a closed position;

FIG. 10 is a top, front, left perspective view thereof in a partially open position;

FIG. 11 is a front view thereof in a closed position;

FIG. 12 is a rear view thereof in a closed position;

FIG. 13 is a left side view thereof in a closed position;

FIG. 14 is another top, front perspective view thereof in a closed position;

FIG. 15 is another bottom, front perspective view thereof in a closed position; and,

FIG. 16 is a right side view thereof in a closed position. The broken lines depict the claim boundary and form no part of the claimed design. The light grey portions shown within the broken lines form no part of the claimed design.
